UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

COUPLING MECHANISM.

1,356,210.

Specification of Letters Patent. Patented Oct. 19, 1920.

Application filed September 6, 1919. Serial No. 322,009.

To all whom it may concern:

Be it known that I, EDMUND P. KINNE, a citizen of the United States, residing at Alliance, in the county of Stark and State 5 of Ohio, have invented certain new and useful Improvements in Coupling Mechanism, of which the following is a specification.

This invention relates to transitional coupling mechanism.

10 In certain foreign countries railway cars are connected to each other by a hook and chain arrangement, adjacent ends of the cars being provided with coöperating buffers to prevent damage to the car structures proper and to retain the cars a predetermined distance apart to prevent the connection from being disturbed. In some of these foreign countries the railway companies are changing over from the hook and chain connection between cars to a connection made 15 by automatic couplers. It will be appreciated that all of the cars cannot be equipped with automatic couplers at the same time, but nevertheless, the cars which are equipped 20 with automatic couplers and those which are not so equipped must be connected in the same train. In other words, there is a transitional period in which adjacent cars may be connected by the old hook and chain 25 arrangement, by an automatic coupler on one car and a hook on an adjacent car connected by a chain, or by two automatic couplers. During this transitional period obviously, it is necessary to have buffers on 30 the cars.

Accordingly one object of my invention is to provide a transitional coupling arrangement whereby railway cars may be connected either by a coupler on one car and a 35 hook on another connected to the coupler by a chain, or by two automatic couplers being connected directly to each other.

Another object is to provide a transitional coupling arrangement adapted to meet all 40 the requirements for successful commercial 45 operation.

These and other objects are accomplished by means of the arrangement disclosed on the accompanying sheets of drawings, in 50 which:

Figure 1 is a fragmentary plan view of two railway cars connected to each other by a 55 automatic coupler, a hook, and a chain connection between the coupler and the hook;

Fig. 2 is a fragmentary plan view of two cars connected by means of automatic couplers, the right hand buffer in each case being removed or moved from its normal position in order that the automatic connection 60 may be made; and

Fig. 3 is a fragmentary side elevation of two cars connected by automatic couplers, certain of the buffers being shown out of their normal positions and in positions to 65 permit connection of the cars by direct engagement of the automatic couplers.

The various novel features of my invention will be apparent from the following description and the drawings and will be 70 particularly pointed out in the appended claims.

Referring to the figures of the drawings, it will be noted that I have shown two railway cars 10 and 11 which are provided with 75 various coupling mechanisms which must be used during the transitional period referred to. Heretofore the railway cars have been connected to each other by means of hooks 12, one of which is shown on car 10 in Fig. 80 1, the hooks on adjacent cars being connected by any suitable flexible connection such as a chain 13. Such cars necessarily are equipped with buffers 14 preferably mounted on the end sills of the car, which buffers coöperate 85 to maintain the cars at a predetermined minimum distance apart.

In Fig. 1 the car 11 is shown equipped with an automatic coupler 15, the knuckle 16 of which is slotted to receive a casting 90 17, the latter being rigidly connected to the former by a pin 18. This casting 17 has its free end terminating at a point adjacent the guard arm 19 whereby it is impossible for the associated link connected thereto to be 95 become accidentally disengaged. The longer of the two connected links which is connected to the shorter link, is connected to the hook 12. It is seen, therefore, how the cars may be connected to each other when one of the 100 cars is equipped with the old time hook and the other car is equipped with an automatic coupler. Of course it is appreciated that the finger or casting 17 is a separate piece which will not be used when two automatic couplers are connected directly to each other. The buffers 14 shown in Fig. 1 perform their usual function.

In order to connect the cars 10 and 11 by couplers directly engaging each other it is 110

necessary that one of the coöperating buffers 14 at each side of the car be removed or moved from its normal position. To meet this requirement I have pivotally mounted the right-hand buffer 14 on each of the cars so that the said buffers may be swung into a position whereby the direct coupling connection may be made. It will be noted when the automatic couplers directly engage each other for making a connection between two adjacent cars the castings or fingers 17 are removed from the knuckles 16. Preferably the buffers in question are pivotally mounted as at 20 and may be swung into their normal position and secured in such position by a pin passing through coöperating eye portions 21 and 22. When the buffers are swung down out of their normal position they are retained in place by a link 23 connected to a hook 24 under the car.

By means of this arrangement cars may be connected to each other whether they are equipped with the old hook arrangement or with automatic couplers or one with one and one with the other, the pivotally mounted buffers being in one position or the other in accordance with the coupler connection being used.

It is my intention to cover all modifications of the invention falling within the spirit and scope of the following claims.

I claim:

1. In combination, a plurality of rail-

way cars adjacent ends of which are provided with coöperating vertically movably mounted buffers movable to a position under the associated car, an automatic coupler connected to one end of one of said cars, and means whereby said coupler may be connected by link to a hook on said other car with said buffers in normal position, and when said other car has an automatic coupler said cars being capable of being connected by direct engagement between the knuckles of automatic couplers when certain of said buffers occupy non-functioning positions under the end of the car.

2. In combination, a plurality of railway cars adjacent ends of which are provided with coöperating buffers, certain of said buffers being pivotally mounted whereby they may be moved from a normal horizontal position to a position under the end of the car to avoid any interference.

3. In combination, a plurality of railway cars adjacent ends of which are provided with coöperating buffers, certain of said buffers being pivotally mounted whereby they may be moved from a normal horizontal position to a position under the end of the car to avoid any interference, and means for retaining the buffers under the end of the car.

Signed at Alliance, Ohio, this 27th day of August, 1919.

EDMUND P. KINNE.
